PHOTOELECTRIC EXPOSURE METER

George Maisch, Sea Cliff, N. Y., assignor to
 Powers Photo Engraving Company, Glen Cove,
 N. Y., a corporation of New York

Application April 19, 1947, Serial No. 742,543

19 Claims. (Cl. 250—41.5)

1

This invention relates to an electrical apparatus and particularly to electric timing means for controlling the duration of exposure in photographic or other processes where the integrated amount of light over an operating cycle is important. The invention is particularly adapted for photographic copying in process camera work where the exposure limits are relatively narrow. However, the invention may be used to control the duration of exposure to light sources rich in ultraviolet, such as mercury arcs for use in sun-tan and medicinal applications. Other applications of the invention will be apparent to those skilled in the art.

In processes where chemical or photo-chemical light action is desired, the integrated value of light over a predetermined time interval or, conversely, a predetermined integrated value of light over a variable time (if the light source varies in intensity) are both of critical importance. As a rule, processes such as photographic require a predetermined product of average light and time of exposure to attain desired results. Due to such variables as distance from and the intensity of a light source, it is advantageous to provide a means which will integrate the effective light over an exposure cycle to determine definite limits for an exposure cycle.

The invention hereinafter described provides a system which is simple, accurate, reliable and which is rugged and may be used by unskilled operators. The invention also provides a system having substantial accuracy over its entire range of operation and having a generally linear operating characteristic permitting simple calibration of the system for a number of ranges.

The invention, in general, provides a condenser shunted by a light responsive resistance, such as a photoelectric cell disposed in a system including a combined rectifier and amplifier and two sources of potential, only one of which is operative on the condenser at any one time. In a normal stand-by condition of the system in preparation for an operating cycle, the condenser is connected to one source of potential for charging. This source may be either direct or alternating, since the amplifier tube also functions as a rectifier during the charging of the condenser. During an operating cycle, the condenser is isolated from the charging potential source and is connected in series with the input or control circuit of the amplifier across the terminals of a constant potential source which functions to clamp or determine the potential for the condenser terminal remote from the vacuum tube.

2

By suitable choice of the clamping potential with respect to the charging potential, the system will maintain the amplifier cut-off during the operating cycle during which time the condenser will discharge. The discharge of the condenser to a predetermined point will terminate the operating cycle. The discharge may be confined to the linear portion of the curve so that calibration of the system is simplified.

10 The two potential sources are regulated to control accurately both the potential to which the condenser is to be charged and the reference potential to which one condenser plate is fixed. This not only provides accurate and sensitive 15 operating characteristics for the system but also endows the system with an immunity to disturbing potentials and makes the system rugged. This is particularly important in the case of energization of the system from a conventional 20 power source, such as a 110 volt, 60 cycle line.

For a more complete description of the invention, reference will now be made to the drawings where Figure 1 shows a circuit diagram of a system embodying the present invention. Figure 2 25 shows a circuit diagram of a modified form.

Transformer 10 has primary 11 whose terminals 12 and 13 are connected to lines 14 and 15 for supplying alternating current from any suitable power source, such as the customary 110 30 volt, 60 cycle supply. Line 15 is provided with switch 16 for controlling the primary circuit. Transformer 10 has filament winding 18 connected to wires 19 and 20 for supplying the heaters of the various vacuum tubes used in the system. Transformer 10 also has filament winding 22 connected to leads 23 and 24 for energizing cathode 25 of rectifier 26. Rectifier 26 has anodes 27 operating in parallel and connected to line 29 going to tap 30 of high potential secondary winding 31. Secondary winding 31 has terminals 32 and 33. Terminal 32 is connected through current-limiting resistor 34 to grounded lead 35. Connected between line 40 and ground is any suitable means for providing voltage regulation. 45 Thus, gas tube 37 having anode 38 connected to line 40 and cathode 39 connected to ground may be provided. Such regulator tubes maintain the peak potential at a constant value and are widely used in various systems.

50 Filament winding 22 for the rectifier has lead 40 connected thereto. Lead 40 is mid-way on the winding so that its potential is half-way between the potentials of the terminals of winding 22 and, thus, is constant relative thereto. Lead 55 40 goes to terminal 41, between which terminal

and grounded lead 35 there is connected condenser 42. Condenser 42 preferably has substantial capacitance and, as will be shown later, functions as a source of constant potential during an operating cycle. By connecting regulator tube 37 in series with rectifier 26, the desired voltage regulation between junction 41 and ground is obtained while providing the gas tube with protection against excessive current flow therethrough.

Connected to junction 41 is a variable resistor consisting of resistor 43 and wiper 44 cooperating therewith. Wiper 44 is connected to one terminal of resistor 45 forming part of a second potentiometer. Resistor 45 has its other terminal connected to grounded wire 35. The resistance network across condenser 42 preferably has substantial value so that, in combination with condenser 42, a resistance-condenser circuit is formed having a time constant for discharge purposes long in comparison to the period of a cycle of power supplied to transformer 18. Cooperating with resistor 45 is wiper 47. Wiper 47 is connected preferably through resistor 48 to junction 49 and thence, by lead 50, to terminals 51, 52, 53, and 54. Terminal 51 has connected thereto one terminal of condenser 56. The other terminal of condenser 56 is connected to line 57. Condenser 56 preferably has a small or moderate capacitance and is adapted to control the duration of an operating cycle for the system.

In order to increase the flexibility of the system, condensers 59 and 60 may be provided. Thus, condenser 59 is connected between junction 53 and terminal 61 of selector switch 61a. Condenser 60 is connected between junction 54 and terminal 62 of the selector switch. Discharge resistor 63 is connected between junction 52 and terminal 65 of the selector switch. The selector switch has fan-shaped contact 66 cooperating with contacts 61 and 62 and small contact 67 cooperating with contact 65 and with contacts 68 and 69 on opposite sides of contact 65. Contacts 68 and 69 are connected to lead 57. By proper design of the selector switch, it is possible to have condensers 59 and 60 both short-circuited through resistor 63, as shown, or to have condenser 59 connected in parallel to condenser 56, or condensers 59 and 60 both connected in parallel to condenser 56. Other means for varying the effective capacitance available between lead 59 and lead 57 may be provided.

Connected between leads 50 and 57 is a light-responsive means such as photoelectric cell 70. Cell 70 may be one of several types and has anode 71 connected to lead 50 and cathode 72 connected to lead 57. Cell 70 is housed in light-tight box 73 having adjusted diaphragm 74 and adapted to be exposed to the light used in the photographic or other process. The cell may be exposed either to the light source, may receive light reflected from the photographic film or sensitive paper, or may be exposed to light transmitted through a photographic negative, for example. The photoelectric cell may conveniently be disposed in fixed relation to the film or sensitive paper, upon which the desired light is focussed, so that the cell itself is automatically affected with the photographic material to variations in distance from the light source or variations in intensity or quality of the light source.

Lead 57 is connected to control grid 75 of vacuum tube amplifier 76. Amplifier 76 is preferably a simple triode, although tubes having more electrodes may be used. Amplifier 76 has filamentary heater 77 connected to leads 19 and 20 for ener-

gization. Amplifier 76 has cathode 78 energized by heater 77, cathode 78 being connected to wire 19 which is grounded as far as the system is concerned. Amplifier 76 has anode 80 connected through load resistor 81 to wire 82 going to tap 29 of the high potential transformer winding. Connected across load resistor 81 is condenser 83.

Anode 80 is also connected to wire 84 going to control grid 85 of amplifier 86. Amplifier 86 is preferably of the type designed to have substantial space current and, while shown as a beam power tube, may be any other suitable type. Amplifier 86 has heater 87 connected to lines 19 and 20. Amplifier 86 has cathode 88 and beam control electrodes 89 and 90 connected together in the usual fashion. Cathode 88 is connected to line 91 going through junction 92 and switch 93 to junction 94. Line 29 is connected to junction 94. Amplifier 86 has accelerating grid 96 connected through dropping resistor 97 to wire 98. Wire 98 is connected to terminal 93 of the high potential winding. Between wire 98 and anode 100 of amplifier 86 are connected condenser 101 and relay winding 102, the latter forming part of relay 103. Relay 103 has movable contacts 104 and 105 respectively. Movable contact 104 is normally open and, for convenience, is shown as bearing against dead back contact 106 in its normal position. Cooperating with movable contact 104 is off-normal contact 107 connected by wire 108 to junction 109 of load 110. Load 110 may be a shutter control winding whose other terminal 111 is connected by wire 112 to terminal 12 of primary winding 11. Terminal 109 is connected by wire 113 and switch 114 to line 15 of the power supply, this latter connection providing a manual shutter control independent of the automatic control exercised by the system. Pilot light 115 across load 110 is provided to show the condition of the load.

Referring back to relay 103, movable contact 105 normally bears against back contact 116 connected by wire 117 and switch 120 to junction 49. Movable contact 105 in the off-normal position cooperates with forward contact 122 connected by lead 123 to junction 92. Between wire 91 and accelerating grid 96 of amplifier 86 is switch 125 for manually terminating an exposure cycle.

Switches 93 and 120 are preferably mechanically interconnected so that they may be operated together. Switch 93 is normally open, and switch 120 is normally closed. They are biased to the position shown in full lines and are adapted to be moved to the dotted line position momentarily by an operator to initiate an exposure cycle.

Wiper 47 may be provided with indicator 127 cooperating with scale 128. Scale 128 may be suitably calibrated to indicate exposure time. It is understood that the calibration of scale 123 will depend upon the adjustment of potentiometer wiper 44. Thus, the potentiometer wiper may be provided with one or more predetermined calibrated positions. A suitable multiplication factor for the potentiometer wiper positions may be provided for scale 128.

The operation of the system is as follows. Assume that switch 16 is closed thus energizing primary 11 of transformer 16. Filament winding 18 will be energized, this being indicated by pilot light 126. Thus, amplifiers 76 and 86 will have their cathodes energized. At the same time, winding 22 will have current therein to energize rectifier cathode 25. It will be apparent that, when terminal 30 is positive with respect to terminal 32 of the high potential winding, current

will flow through rectifier 26 and also through regulator tube 37.

Rectified current passing through 26 will go along lead 40 to junction 41. From junction 41, charging current will flow to condenser 42 and thence to ground. After a short time, condenser 42 will become charged to the maximum potential available. Switches 93, 120 and 125 are in the full-line position. For simplicity, the selector switch will be assumed to be in the position shown where only condenser 56 will be used. Since relay 103 is in the normal position shown in the drawing and since switch 93 is open, power tube 86 cannot conduct. During this time, positive surges along line 29 will go through junction 94, relay contact 105, normal back contact 118, lead 119 and normally closed switch 120 to junction 49. From junction 49, positive surges will go to terminal 51. Upon the occurrence of each positive surge, charging current can flow into condenser 56. The circuit goes on from condenser 56 to line 57 and control grid 75 of vacuum tube 76. The flow of charging current for condenser 56 will maintain grid 75 at or above cathode potential and grid current to cathode 78 will be established. Thus, for surges when terminal 30 is positive to terminal 32 of the high potential winding, a complete charging circuit for condenser 56 will be established. Resistor 34 will limit the charging current to a safe value. It is preferred to design the time constant of the charging circuit for condenser 56 so that condenser 56 will be charged in several cycles. For a 60 cycle supply, the time constant may be equal to the period of about two or three cycles. This, however, is exemplary and, with the addition of other condensers, may be varied to suit the operating range of the system. In actual practice, some current from grid 75 to cathode 78 will generally flow even after condenser 56 has become what may be considered, for all practical purposes, fully charged. This current will be due to the fact that the photo cell may conduct to some extent and the fact that the grid potential tends to remain at or slightly above the potential of the cathode. Leakage through the condenser, as well as the leakage resistance present between the grid and cathode of tube 76, will also be a factor. If desired, the leakage across the terminals of condenser 56 may be stabilized by a suitable grid resistor connected between grid 75 and cathode 78.

Since condenser 56 is charged, the system may be considered to be in a stand-by condition and ready for an operating cycle. Assuming that an exposure is to be made, switch 93 is momentarily closed and switch 120 is simultaneously opened. As will be explained later in connection with the charging circuit, the opening of switch 120 serves to definitely cut-off tube 76 and thus to cut off the flow of load current through resistor 81. In practice, condenser 83 is small enough that it discharges quicker than switch 93 and switch 120 can be opened. Thus, the potential of control grid 85 and cathode 88 are equalized to the potential present at terminal 30. It will be apparent that, with the closure of switch 93, a complete circuit for space current through the power tube is established. During the positive portions of each cycle, space current tends to flow through power tube 86. When power tube 86 conducts, the current through relay winding 102 will suffice to close relay contacts 104 and 105. The closure of relay contact 104 against back contact 107 will close the load circuit which, in this instance, con-

sists of winding 110. Condenser 101 will filter out the current surges. Thus, if winding 110 controls a shutter, it will be apparent that an exposure cycle will thereupon be initiated.

Relay contact 105 is pulled to forward contact 122 and thus effectively short-circuits switch 93. Hence, when switch 93 is opened, the system will continue to operate during an exposure cycle. Thus, the switching position in its off-normal position permits the system to go through an operating cycle. When movable contact 105 is away from normal contact 118, the charging circuit from terminal 30 of the transformer winding to condenser 56 will be broken. It is apparent that the potential of junction 49, when the relay is in a normal position, will vary from a high positive to a high negative value with respect to ground. Hence, when the relay breaks the charging circuit for condenser 56, the instantaneous potential of junction 49 may, at the moment of break, be anywhere between two extreme values. However, resistor 48 is high enough so that the tendency to charge or discharge condenser 42 will be negligible during the time that junction 49 is going through its potential extremes. Thus, during normal or charging circuit conditions, the constant potential source is practically isolated from condenser 56. Upon the break of the charging circuit to condenser 56, the potential of junction 49 quickly reaches a value determined by the position of wiper 47. The potential of wiper 47 to ground is maintained constant. Thus, junction 49 is clamped to a fixed potential above ground.

It is apparent that the potential of junction 41 only differs from the peak potential at terminal 30 by the drop through rectifier 26 and load resistor 34. Thus, junction 51 will assume a potential positive with respect to ground but at some intermediate value between ground and the positive peaks at terminal 30 depending upon the position of wiper 47 in the network. The potential of grid 75 will drop below ground by a corresponding amount, depending upon the position of wiper 47. The amount of this drop will be illustrated later in connection with a circuit having specific values. The drop in grid potential will suffice to cut tube 76 off.

During the course of an exposure or operating cycle, photo-electric cell 70 functions as a resistor whose value is a function of the light intensity at the cathode. It is understood that, in case cell 70 is of the type generating a potential, the action is similar. In such a case, the potential generated by the cell may be considered as a negative resistance having a value functionally related to the light. Cell 70 thus provides a discharge path for condenser 56. Since the potential of junction 51 is maintained constant with respect to ground, it is apparent that the potential of grid 75 will rise. During the exposure cycle, tube 76 remains cut off. However, when the discharge of condenser 56 has run a predetermined course, the potential of control grid 75 will rise to a cut-in value for amplifier 76. Upon cut-in of amplifier 76, the potential of anode 80 will drop. This will cause the potential in line 84 to drop and thus result in a drop in potential of control grid 85 of power tube 86. The drop in potential across load resistor 81 is so designed that tube 86 will thereupon be cut off.

When tube 86 is cut-off, current through relay winding 102 stops, and the relay assumes its normal position. This breaks the load circuit to winding 110 and determines the end of an exposure period or other operating cycle.

The difference in potential between wiper 47 and ground or cathode 78 is a measure of the potential through which control grid 75 is depressed below cut-off. Assuming for the sake of simplicity that tube 76 cuts-off when the control grid becomes negative to the cathode (this is merely an assumption and is not essential to the operation of the system), the higher the potential of wiper 47 above ground, the less will be the drop of potential of control grid 75 below ground. Thus, as a practical example, assume that the potential across condenser 42 is 140 volts. Also assume that the potential across condenser 56 is 140 volts. In the system disclosed, the potential across condenser 56 may be somewhat higher due to the drop through rectifier 26. However, this is not important, and the potential across the two condensers may be equal, or the potential across condenser 56 may be greater or less than that across condenser 42.

Assuming, however, as above, that junction 41 is plus 140 volts, junction 51 will be a bit less than 140 volts when condenser 56 is fully charged. Now assume that the potential of wiper 47 is plus 30 volts. Upon the initiation of an operating cycle and during the course of this operating cycle, the potential of junction 51 will be clamped to plus 30 volts. However, at the beginning of the operating cycle, grid 75 will drop to minus 110 in order to maintain the 140 volts across condenser 56.

It follows that condenser 56 will have to discharge to the point where the potential across the condenser will be 30 volts. Thus, a long exposure cycle will occur.

If the potential of wiper 47 is adjusted to plus 100 volts, it follows that grid 75 will be dropped 40 volts below ground.

As disclosed herein, resistor 43 and wiper 44 forming an auxiliary potentiometer are disposed on the high potential side of resistor 45. With such an arrangement, it is evident that the operating range for condenser 56 is in the upper portion of the potential discharge curve for this condenser. It is possible, however, to dispose resistor 43 and wiper 44 on the low potential side of resistor 45 so that, in the operating range of the system as controlled by wiper 47, condenser 56 will never discharge completely. While such a modified system functions in an efficient and satisfactory manner, it has been found that such a modified system may be somewhat sensitive to variations in tubes incident to replacement. It is possible that capacitance to ground of various components of the system, as well as conducting characteristics of photo-cell 70, may account for such increased sensitivity.

The operating characteristics and time constants of the various circuits may most easily be discussed in connection with a system having specific constants and potentials. Thus, in one system, regulator tube 37 was type VR150 available in the market and sold by Radio Corporation of America and others. Such a tube tends to limit the potential across the electrodes to a peak of 150 volts. Rectifier 26 was a 5V4 of the full-wave type, the two portions of the rectifier being connected as shown to provide a simple half-wave rectifier. Amplifier 76 was a 6J5, while power tube 86 was type 6V6. Photoelectric cell 70 was type 929. Resistor 34 had a value of about 5000 ohms. Resistors 43 and 45 each had values of 5000 and 10,000 ohms respectively.

Resistor 48 had a value of 100,000 ohms, re-

75 sistor 97 had a value of about 30,000 ohms, and resistor 81 had a value of about one megohm.

Condensers 42 and 101 each had values of 12 microfarads. Relay 103 was a simple relay which could be operated with space current through the beam tube. Condenser 56 had a capacitance of about one-half microfarad, while condenser 83 had a capacitance of about .05 microfarad. The R. M. S. open circuit potential of terminal 30 with reference to terminal 32 was 140 volts, and the corresponding potential of terminal 33 with respect to terminal 32 was 440 volts. Condenser 59 was .5 microfarad and condenser 60 was 4 microfarads.

In the practical system, identified above, the time constant for charging condenser 56 alone is 2500 microseconds. With a sixty-cycle power source, a period for the power source is almost 17,000 microseconds. Thus, condenser 56 can be completely charged in about ten cycles. The time constant for charging condenser 42 is about 60,000 microseconds while the discharge circuit time constant is between about 120,000 and about 240,000 microseconds. The time constant for the discharge circuit of condenser 56 will depend upon the light falling on cell 70, assuming switch 93 is open and tube 76 cut off. However, as long as tube 76 is cut off, the time constant of the shunt circuit comprising wiper 47, resistor 48, the condenser and photoelectric system, grid 75 to ground is theoretically infinite and practically very long. Even when grid 75 is above cut-off, the time constant of this circuit is very large. Hence, it is evident that wiper 47 carries little if any current, and the potential of wiper 47 during an exposure cycle is constant.

It is possible to have the resistance network around condenser 42 much higher, say about 100,000 ohms or the like, and eliminate resistor 48. However, the arrangement shown is convenient for potentiometer control and satisfactory tolerances may be easily maintained. Furthermore, there is sufficient current flow around condenser 42 so that any sudden shifts in potential at wiper 47 are quickly dissipated.

For expanding the range of operation of the system, condensers 59 and 60 may be relied upon or diaphragm 74 may be adjusted to control the amount of light impinging on the cathode of the photoelectric cell. Thus, condenser 59 may be about one-half micro-farad and condenser 60 may be four micro-farads. Other values, however, may be selected. Resistance 63 may have any desired value, as 5000 ohms, to discharge the condensers when they are not to be used.

It is evident that, if diaphragm 74 is closed to reduce the amount of light on cell 70, the ratio of diaphragm areas may be used as a multiplying factor for increasing the operating range of the system. It is also possible to use the diaphragm in a manner to bring the cell response to a desired level to calibrate the entire system. This is particularly advantageous with the present system, since all variables are linear and provide a variety of operating ranges.

At any time during an operating cycle, the cycle may be terminated at will by closing switch 125. This drops the potential of accelerating grid 96 down to cathode potential and cuts off the beam tube. The relay thereupon opens and the system reverts to normal.

Referring now to Figure 2, a modification is shown wherein the high side of condenser 56 is

connected to the charging potential source in the normal relay position and connected to the source of constant potential (wiper 47) in the off-normal relay position corresponding to an operating cycle. The circuits are generally the same. Center tap 30 of transformer secondary 31 has connected thereto resistor 30a, this going to the junction of wire 82 and lead 29'. Lead 29', it will be noted, only extends to the anode of rectifier 26. Cooperating with resistor 30a is wiper 30b connected by wire to junction point 94. By virtue of this change, greater precision in setting the system for zero or short exposures is possible. This change, if desired, may be incorporated in the system shown in Figure 1. An additional movable contact 105' is provided. Contact 105' normally bears against back contact 118' connected to movable contact 105. Movable contact 105' is connected by lead 50' to the high side of condenser 56. Wiper 47' is connected by wire 48' to forward contact 122'. The back contact for movable contact 105 is unnecessary. Switch 120' movable with switch 93 serves to short load resistor 81 and make the potentials of grid 85 and cathode 88 equal.

A charging circuit for condenser 56 is established from movable contact 105' to contact 118', movable contact 105' and wire 50'. When manual switch 93 is closed power tube 86 becomes conducting and the relay locks in position. Thereupon, the charging circuit to condenser 56 is broken, and wiper 47' is connected to condenser 56 through movable contact 105' and fixed contact 122'. In other respects the modification shown in Figure 2 is generally similar to the embodiment illustrated in Figure 1.

In both circuits, it is necessary that the potential of wiper 47 or 47' with respect to the cathode of tube 76 be higher than the potential of grid 75 to cathode 78 at cut-off. Thus, when condenser 56 discharges, grid 75 can cut-in tube 76 and terminate the operating cycle. In other words, the difference of potential across condenser 56 when fully charged must be greater than the potential between the tube cathode and cell anode at the beginning of an operating cycle due to the constant potential source.

What is claimed is:

1. In a system of the character described, a photoelectric cell having cathode and anode and exposed to light during an operating cycle, a condenser connected across said cell, a vacuum tube having at least cathode, control grid and anode, an output circuit including a load connected to the tube cathode and anode, a connection between the grid and cell cathode, two sources of potential at least one of which is a source of constant potential, connections from the tube cathode to the negative terminal of said one constant potential source and to one terminal of the second potential source respectively, means including switching means having normal and off-normal positions for impressing selectively the potential of the remaining terminal of each potential source upon the cell anode, said switching means in the normal position providing a circuit for charging said condenser with grid current furnished by said second potential source, said switching means in the off-normal position during an operating cycle providing a circuit for clamping the cell anode potential to the positive terminal of said constant potential source while the cell discharges the condenser during the operating cycle, said clamping potential being above grid cut-off whereby said tube is cut-off during

the operating cycle and cuts in to terminate the operating cycle.

2. The system of claim 1 wherein said load includes means responsive to space current through said vacuum tube for maintaining said switching means in off-normal position during an operating cycle after the initiation thereof and for returning said switching means to a normal position when said tube cuts in at the termination of an operating cycle.

3. The system according to claim 1 wherein means are provided for varying the potential of the positive terminal of the source of constant potential and wherein indicating means are associated with said varying means for indicating the duration of an operating cycle.

4. In a system of the character described, a photoelectric cell having cathode and anode and exposed to light during an operating cycle, a condenser connected across said cell, a vacuum tube having at least cathode, control grid and anode, an output circuit including a load connected to the tube cathode and anode, a connection between the grid and cell cathode, a source of constant potential including a second condenser and resistance combination, a second source of potential, connections from the tube cathode to the negative terminal of said constant potential source and to one terminal of the second potential source respectively, a potentiometer connection to the resistance of said constant potential source, means including switching means having normal and off-normal positions for impressing selectively the potential of the potentiometer connection and remaining terminal of the second potential source upon the cell anode, said switching means in the normal position providing a circuit for charging said first condenser with grid current furnished by said second potential source, said switching means in the off-normal position during an operating cycle providing a circuit connecting the potentiometer connection and cell anode for clamping the cell anode potential to said potentiometer potential while the cell discharges the condenser, said clamping potential being above grid cut-off during the operating cycle and cuts in to terminate the operating cycle.

5. The system of claim 4 wherein said potentiometer connection is connected to said cell anode through a high resistance in both switch positions, said potentiometer connection being substantially isolated from said cell anode in the normal position of said switching means.

6. The system of claim 4 wherein indicating means are provided for said potentiometer connection, said indicating means being adapted to show the duration of an operating cycle corresponding to the setting of said potentiometer connection.

7. In a system of the character described, a photoelectric cell having a cathode and anode and exposed to light during an operating cycle, a first condenser connected across said cell, a vacuum tube having at least cathode, control grid and anode, an output circuit including a load connected to the tube cathode and anode, a connection between the grid and cell cathode, a source of constant potential including a second condenser and resistance connected across said second condenser, a source of alternating potential, connections from the tube cathode to the negative terminal of said second condenser and to one terminal of the alternating potential source respectively, means including switching means having normal and off-normal positions for im-

pressing selectively the potential of the remaining terminal of said alternating potential source and a point on said resistance upon the cell anode, said switching means in the normal position providing a circuit for charging said first condenser from the alternating current source with grid current, said switching means in the off-normal position during an operating cycle providing a circuit for clamping the cell anode potential to said point on said resistance while the cell discharges the first condenser, said clamping potential being above grid cut-off whereby said tube is cut off during the operating cycle and cuts in to terminate the operating cycle.

8. The system of claim 7 wherein potentiometer means are provided for selecting a point on said resistor and wherein indicating means coupled to said potentiometer are provided for showing the duration of an operating cycle.

9. The system of claim 7 wherein the circuit between said cell anode and point on said resistance includes a potentiometer connection and high resistance, said circuit being closed in both positions of said switching means.

10. The system of claim 7 wherein means responsive to flow of current is provided in said load for maintaining said switching means in off-normal position after the initiation of an operating cycle and for the duration of said operating cycle and for returning said switching means to the normal position when said tube cuts in to terminate the operating cycle.

11. In a system of the character described, a photoelectric cell having cathode and anode and exposed to light during an operating cycle, a condenser connected across said cell, a vacuum tube having at least cathode, control grid and anode, an output circuit including a load connected to the tube cathode and anode, a connection between the grid and cell cathode, a source of alternating potential, a rectifier and second condenser in series across said potential source, the common connection between the second condenser and rectifier having a positive polarity with the remaining second condenser terminal having a negative polarity, a connection between the tube cathode and negative terminal of said second condenser, a resistance network shunted across said second condenser, a potentiometer connection on said resistance network for determining a point on said network having a predetermined constant positive potential with respect to said vacuum tube cathode, said second condenser and resistance network having a time constant for discharging substantially greater than the period of a cycle from the alternating potential source, means including switching means having normal and off-normal positions for impressing selectively the potential at the rectifier anode and potentiometer connection upon the cell anode, said switching means in the normal position providing a circuit for charging the first condenser from the alternating potential across said source with said tube cathode and grid rectifying the current, said switching means in the off-normal position during an operating cycle providing a circuit for clamping the cell anode potential to said potentiometer connection while the cell discharges the first condenser, said clamping potential being above grid cut-off whereby said tube is cut-off during the entire operating cycle and cuts in to terminate the operating cycle.

12. The system of claim 11 wherein means are provided for maintaining constant the peak potential across said alternating potential source

during portions of the cycle when the rectifier anode is positive.

13. In a system of the character described, a photoelectric cell having cathode and anode and exposed to light during an operating cycle, a first condenser connected across said cell, a vacuum tube having at least cathode, control grid and anode, an output circuit including a load connected to the tube cathode and anode, a connection between the grid and cell cathode, a source of alternating potential having one terminal connected to said tube cathode, a rectifier and second condenser connected in series across said alternating potential source, said rectifier having its anode connected to the other terminal of said alternating potential source, said second condenser having its negative terminal connected to the one terminal of said alternating potential source, a resistance network shunted across said second condenser, a potentiometer connection on said resistance network for determining a point having a predetermined positive potential with respect to the tube cathode, means for maintaining constant the peak potential across the terminals of said alternating potential source during those portions of a cycle when said rectifier can conduct, means including switching means having normal and off-normal positions for impressing selectively the potential of the rectifier anode and potentiometer connection upon the cell anode, said switching means in the normal position providing a circuit for charging said first condenser with current furnished by said alternating potential source and rectified by the cathode and grid of said tube, said switching means in the off-normal position during an operating cycle providing a circuit for clamping the cell anode potential to said potentiometer connection while the cell discharges the first condenser, said clamping potential being above grid cut-off whereby said tube is cut-off during the entire operating cycle and cuts in to terminate the operating cycle.

14. The system of claim 13 wherein a high resistance connection between said potentiometer connection and cell anode is provided in all switch positions.

15. The system of claim 13 wherein indicating means are associated with said potentiometer for showing the duration of an operating cycle.

16. The system of claim 13 wherein means are provided for controlling the amount of light admitted to the photoelectric cell for determining the operating range of the system.

17. In a system of the character described, a photoelectric cell having cathode and anode, a first condenser connected across said cell, a first vacuum tube having cathode, control grid and anode, a connection between the grid and cell cathode, a source of alternating potential having ground, intermediate and high potential terminals respectively, a rectifier and second condenser connected in series across said intermediate and ground terminals, the grounded condenser terminal having a negative polarity, a regulator tube for controlling the peak potential connected across said second condenser for maintaining constant the positive peaks with respect to ground, a resistance network shunted across said second condenser, a variable potentiometer wiper cooperating with said resistance network for selecting a point on said resistance network positive with respect to ground, said wiper having indicating means to show the duration of an operating cycle, said second condenser and resistance network having a long time constant,

13

connection including a high resistance between said potentiometer wiper and cell anode, a relay circuit connecting the intermediate terminal and cell anode, said circuit when closed being adapted to provide charging current for said first condenser, said cell anode being adapted to be clamped to the potentiometer wiper when said relay circuit is open, a second vacuum tube having cathode, control grid and anode, a circuit including a manual switch for connecting said second tube cathode to the intermediate terminal and second tube anode to the high potential terminal, a connection between the control grid of said second tube and the anode of said first tube, a load resistor connected between the anode of said first tube and said intermediate terminal, relay means in the cathode-anode circuit of said second tube, said relay means having normal and off-normal positions corresponding to non-conducting and conducting conditions respectively in said second tube, said relay having circuit connections for maintaining open the relay circuit between the intermediate terminal and cell anode

14

when said relay is in off-normal position and for maintaining said relay circuit closed when said relay is in the normal position, said manual switch, upon closure being adapted to cause the cathode-anode circuit of said second tube to move said relay to an off-normal position and maintain the charging circuit to said first condenser open with said first tube remaining at cut-off during the operating cycle and cutting in at the termination of said operating cycle to cut-off the second tube and return said relay to a normal condition.

18. The system of claim 17 wherein means are provided for determining the amount of capacitance across said cell to determine the operating range of the system.

19. The system of claim 17 wherein said cell has means for adjusting the amount of light thereon to determine the operating range of the system.

GEORGE MAISCH.
